(57) **CLAIM**

The ornamental design for a “shovel with movable target handle,” as shown and described.

DESCRIPTION

FIG. 1 is a perspective view of the shovel with movable target handle, showing my design, wherein the movable target is shifted toward the end of the handle;

FIG. 2 is a perspective view of the shovel with movable target handle, showing my design, wherein the movable target is shifted toward the shaft of the shovel;

FIG. 3 is a perspective view of the shovel with movable target handle, wherein the movable target is shifted to the middle of the handle;

FIG. 4 is a rear perspective view of FIG. 1;

FIG. 5 is a front elevation view of FIG. 1;

FIG. 6 is a front elevation view of FIG. 2;

FIG. 7 is a front elevation view of FIG. 3;

FIG. 8 is a rear elevation view of FIG. 1;

FIG. 9 is a right side elevation view of FIG. 1;

FIG. 10 is a left side elevation view of FIG. 1;

FIG. 11 is a top plan view of FIG. 1; and,

FIG. 12 is a bottom plan view of FIG. 1.

The broken lines depict portions of the design that form no part of the claimed design.
